UNITED STATES PATENT OFFICE.

CHARLES E. PAQUIN, OF TAUNTON, MASSACHUSETTS.

SPLICING-YARN CLAMP AND CUTTER DEVICE.

1,173,377.

Specification of Letters Patent. Patented Feb. 29, 1916.

Application filed February 20, 1915. Serial No. 9,685.

To all whom it may concern:

Be it known that I, CHARLES E. PAQUIN, a citizen of the United States, residing at Taunton, in the county of Bristol and State 5 of Massachusetts, have invented certain new and useful Improvements in Splicing-Yarn Clamp and Cutter Devices, of which the following is a specification.

This invention relates to the general subject of circular or rotary knitting machines, and has particular reference to machines of this type which utilize a splicing thread in 10 the knitting of hosiery.

Heretofore, in the manufacture of the so-called high-spliced heel and double-sole hosiery, it has been the more common practice to sever the portion of the splicing thread which is not knit into the stocking, by hand, often injuring the goods through inaccuracy 15 or carelessness of the operator. This method involved a separate operation which was not only time consuming, but at the same time expensive through the loss of at least two per cent. of the product on account of holes 20 being cut therein. Accordingly, the present invention contemplates the severing of these floating threads from the web of the stocking during the process of knitting, thereby not only facilitating the manufacture of this 25 class of hosiery, but also reducing the factory loss on account of seconds or other imperfections to a minimum.

A primary object of the invention is to provide a novel and effective clamping or 30 binder device for the floating splicing thread which will tightly grip the same so that it will be held taut as it is advanced against a stationary cutter blade to be severed close to the main web of the stocking. Viewed 35 in this, its primary aspect, the invention also provides a distinct advantage in the manufacture of this class of hosiery since it makes it possible to knit the splicing thread into the stocking while the needle cylinder is 40 moving in its usual rotary manner. That is to say, the employment of the present clamp or binder device makes it unnecessary to change the motion of the knitting cylinder from rotary to reciprocating, thereby eliminating the numerous and expensive parts 45 usually necessary in machines of this character to alternate the motion of the needle cylinder.

A further object of the invention is to 50 provide a novel, simple and practical clamp or binder device for the floating splicing

yarn which may be adjusted so as to tightly clamp the yarn so that it will be automatically cut uniformly even on both sides of the stocking. Furthermore, the arrangement 60 and type of clamp or binder contemplated by the present invention makes it possible for the floating splicing yarn to have a free unobstructed passage across the top of the carrier plate which prevents it from being 65 prematurely cut or ruptured by any other means than the specially provided cutter, thereby insuring higher efficiency of the machine and preventing the stocking from being cut as it goes under the ring. 70

With the above and other objects in view which will more readily appear as the nature of the invention is better understood, the same consists in the novel construction, combination, and arrangement of parts hereinafter more fully described, illustrated, and claimed. 75

A preferred and practical embodiment of the invention is illustrated in the accompanying drawings, in which— 80

Figure 1 is a top plan view of the latch ring having the thread guides and other parts incident to this portion of a rotary knitting machine, and showing the course of the floating splicing threads from the splicing yarn guide to a point adjacent the stationary cutter. Fig. 2 is a vertical section on the line 2—2 of Fig. 1 showing a portion of a rotary knitting machine with the needle cylinder, latch ring, and adjacent parts, together with the novel and improved binder or splicing yarn clamp. Fig. 3 is a vertical section on the line 3—3 of Fig. 1. Fig. 4 is a vertical section on the line 4—4 of Fig. 1 showing the splicing yarn guide raised in full lines so that the binder device is open, and also showing the splicing yarn guide by dotted lines in the position in which the splicing yarn is knit into the stocking. Fig. 5 is an enlarged detail sectional view of the splicing yarn clamp shown in Fig. 4. Fig. 6 is an enlarged detail front elevation showing the floating splicing yarn clamp open. Fig. 7 is a view similar to Fig. 6 showing the relative position of parts when the main-thread shear device is operated. 95

Similar reference characters designate corresponding parts throughout the several figures in the drawings. 110

In carrying out the present invention, it is proposed to utilize the same in connec-

tion with the well-known "Banner" type of knitting machine, and as shown in the several figures of the accompanying drawings, the numeral 1 designates the usual rotary 5 needle or knitting cylinder having mounted therein the circular bank of knitting needles 2, while arranged above the needle cylinder and its several parts is the usual latch ring 3 which includes the latch ring sup- 10 port 4. The knitting cylinder is of the usual construction and is given its rotation by the usual mechanism (not shown). The said latch ring 3 is preferably provided upon the side thereof with a supporting 15 extension 5 to which is secured a bracket arm 6 having formed at one end a depending bifurcated portion 7 which carries at its lower end a segmental plate member 8 occupying the usual position within the 20 latch ring 3 and above the knitting cylinder 1. This segmental plate member 8 is provided with a cutter segment 9 having thereon a stationary splicing yarn cutter 10 in the form of an upstanding triangular 25 knife blade, and is also provided with a shearing edge 11 which cooperates with the usual swinging shear blade 12 for cutting the main yarn. For the purpose of maintaining the proper relation of the shearing 30 edge 11 and shear blade 12, a suitable flat spring 13 is employed, and it will also be noted in connection with this blade 12 that the same is provided with a rounded nose portion and its back edge is flattened to 35 form a clamping-edge 12^a. The main yarn shear blade 12 has a link connection 14 with a main operating lever 15 pivotally mounted on the bracket arm 6 as at 16, and oper- 40 atively connected to the usual fashion or pattern wheel (not shown) through a suitable connection 17.

At one side of the bracket arm 6 is preferably arranged a main-yarn binder 18 which is pivotally mounted as at 19 and has 45 its lower edge normally held in contact with the upper face of the segmental plate 8 by means of a spring 20. This main-yarn clamp 18 is preferably of forked formation, providing a splicing yarn clearance and 50 guide 21, and is also cut away as at 22 to permit the same to tilt on the pivot 19 under the action of a presser bar 23 carried by the link 14. It will thus be apparent that when the pattern device actuates the lever 55 15 through the connection 17, the link 14 is thrust downwardly separating or opening the shears 11 and 12, and also carrying the presser bar 23 downward to lift the clamp 18 from the face of the segmental plate 60 member 8.

While the foregoing details of construction relate more specifically to instrumentalities operable in connection with the main-yarn or thread from which the web of 65 the stocking is knit, they are referred to in

order to assist in a proper understanding of the improved splicing yarn binder contemplated by the present invention.

Referring now to the action and details of the splicing yarn binder or clamping device, it will be observed that the same essentially comprises a main clamp arm 24 which is pivoted as at 25 to one of the members of the bifurcated portion 7 of the bracket arm 6, and a tension spring 26 having its ends respectively connected to the clamp arm 24 and the bracket 6. This tension spring 26 normally holds the flat edge 27 of the clamping arm 24 in contact with the clamping edge 12^a of the shear blade 12, thereby providing a splicing yarn clamp 12-24.

It will be noted that the spring 13 serves to maintain the proper relation between the shear blade 12 and the shearing edge 11, and also holds the clamp arm 24 and clamp blade 12 in proper vertical alignment so that there is no possibility of the edges 12^a and 27 not being in effective contact, thereby insuring a positive gripping clamp for the splicing yarn thread. The said clamp arm 24 is also provided with a smooth yarn guide nose 28 to prevent the floating splicing yarn from being accidentally caught, and on its rear side carries an adjustable yarn retainer plate 29 which may be adjusted through the medium of the screw 30 and slot 31 in the body of the arm 24 so that its pointed thread retainer end 29^a not only overlaps with or crosses the joint formed by the edges 12^a and 27 of the clamping jaw, but also provides a lateral hook or stop which prevents the thread from being withdrawn from between the edges of the jaws above mentioned. This construction, therefore, provides a very tight and effective grip for the floating splicing yarn so that it will be held taut when it goes against the stationary cutter 10 as the needle cylinder rotates. It will accordingly be understood that the gripping position of the clamp arm 24 is as shown in Fig. 2, and it will also be apparent that it is in this position that the floating yarn is gripped to be cut as it travels against the triangular cutter blade 10.

The clamp arm 24 is actuated or raised through the medium of a lever 32 which is pivoted as at 33 to one of the bifurcated members of the bracket arm 6, and has its end 34 normally resting upon the clamp arm 24 as shown in the several figures of the drawings, while its opposite end is angled as at 35 and is always in contact with the yarn guide 36 which feeds the splicing yarn S into the stocking. This latter feature can be best observed from Fig. 4 of the drawings which shows in full lines the splicing yarn guide 36 raised so that the splicing yarn S is not being knit into the stocking, and shows in dotted lines the position of the

splicing yarn guide when the splicing yarn is being knit into the stocking. The said splicing yarn guide 36 is actuated by the ordinary cam means for this purpose (not shown), so that for one-half of the revolution of the rotary knitting cylinder, the splicing yarn is knit into the stocking, while for the other half of the revolution, the splicing yarn does not go into the stocking but passes across the top of the segmental plate member 8. It will thus be apparent that after a half round of the splicing thread S has been knit into the stocking, the splicing yarn guide 36 is raised so that the said splicing yarn is held above the needles and not woven into the stocking, and while the yarn guide 36 is in its raised position, the end 35 of the lever 32 is also raised so that the clamping arm 24 of the binder device is turned on its pivot to open the jaws 12^a and 27. This position of the jaws of the splicing yarn binder permits the splicing yarn S to pass freely through the splicing yarn clearance 21 of the main thread binder 18 across the upper surface of the segmental plate member 8 and in close proximity to the sharpened edge of the stationary cutter blade 10 as clearly shown in Figs. 1 and 4. Thus, it is obvious that if the rotating needle cylinder 1 is traveling in the direction of the arrow in Fig. 1, the portion of the stocking describing a semi-circle to the right of the plate member 8 in said figure, has woven therein the splicing thread as indicated by double dotted lines, while the remaining semi-circle to the left of the plate member does not have the thread as indicated by a single dotted line, but the same passes over the top of the plate member 8 between the clamping edges 12^a and 27 which are open. At a predetermined instant at this point of the knitting, the splicing yarn guide 36 is lowered to start the insertion of the splicing yarn for the next half round, and the clamp arm 24 is lowered onto the top edge of the knife blade 12 thus clamping the splicing thread between the edges 12^a and 27 so that as the cylinder continues to revolve, the thread is held taut and severed by the stationary cutter 10 close to the web of the stocking. This severing of the splicing thread leaves a loose portion S' between the cutter 10 and the edges 12^a and 27, which latter are closed as the next half round of splicing is being knit in the stocking, and also leaves another portion S², on the other side of the clamp, which has a connection, approximately for instance, at S³ with the web of the stocking, and as the cylinder continues to rotate, this portion S² is brought around toward the cutter 10 so that it is severed by the same close to the web in the same manner as above described. Therefore, the piece of splicing yarn, comprising the sections S' and S², which is

clamped between the jaw edges 12^a and 27 is automatically severed at both ends from the stocking and falls out of the jaws when they are opened to receive the next floating splicing thread. In other words, the floating splicing thread S when extending across the top of the segmental plate members is tightly gripped at its center by the edges 12^a and 27 to accomplish the severing of the portion S' from the main web of the stocking, while the portion S² is folded toward the loose portion S' and also toward the cutter 10 as the cylinder continues to rotate, to be severed by the said cutter. This construction enables the clamp arm 24 of the binder device which co-operates with the flat edge 12^a of the shear blade 12 to perform the dual function of a binder or clamp for the splicing yarn thread as one portion thereof is carried against the cutter 10, and also holds the remainder of the floating thread in such a position that it is severed by the same cutter upon the continued rotation of the needle cylinder. Another advantage of this arrangement resides in having only a single stationary cutter to successively sever both ends of the floating splicing yarn, which it effectively does by first cutting one end and then having the other end folded toward the loose or previously severed end to be carried against the same cutter.

From the foregoing description, it is thought that the many features and advantages of the invention will be readily apparent, and it will of course be understood that various changes in the form, proportion, and minor details of construction may be resorted to without departing from the spirit or sacrificing any of the advantages of the invention.

I claim:

1. A circular knitting machine including, in combination with the knitting mechanism and the main yarn cut-off, a splicing thread cutter, and a splicing-thread clamp partly formed by the main yarn cut-off.
2. A circular knitting machine including, in combination with the knitting mechanism and a shear blade of the main yarn cut-off, a stationary splicing thread cutter, and an automatically operated clamping member co-operating with said blade to form a clamp for the splicing thread.
3. A circular knitting machine including, in combination with the knitting mechanism and a shear blade of the main yarn cut off, a stationary splicing thread cutter, a clamping member co-operating with said blade to form a clamp for the splicing thread, and means for automatically operating the said clamping member intermittently.
4. A circular knitting machine including, in combination with the knitting mechanism and a shear blade of the main yarn cut

off, a stationary splicing thread cutter, a spring retracted clamping member coöperating with said shear blade to form a clamp for the splicing thread, and means for automatically lifting said clamping member intermittently from the shear blade.

5. A circular knitting machine including, in combination with the knitting mechanism and shear blade of the main yarn cut off, a stationary splicing thread cutter, and an automatically operated clamping member having a guard nose and coöperating with said blade to form a clamp for the splicing thread.

10 6. A circular knitting machine including, in combination with the knitting mechanism and a shear blade of the main yarn cut off, a stationary splicing thread cutter, and an automatically operated clamping member carrying an adjustable yarn retainer plate having a guard nose for coöperating with said blade to form a clamp for the splicing thread.

15 7. A circular knitting machine including, in combination with the knitting mechanism and a main-yarn shear blade, of a splicing

yarn clamping member having a flat clamping edge coöperating with said main-yarn shear blade, a yarn retainer plate carried by said clamping arm, means for holding the 30 said clamping member in contact with the main shear blade, and means for operating said clamping arm.

8. A circular knitting machine including, in combination with the knitting mechanism and a main-yarn shear blade, of a splicing yarn clamping member having a clamping edge coöperating with said main-yarn shear blade, an adjustable yarn retainer plate carried by said clamping arm 40 and having a guard nose adapted to provide a lateral yarn stop, spring means for holding the clamping member in contact with the main yarn shear blade, and lever means for operating said clamping arm. 45

In testimony whereof I hereunto affix my signature in the presence of two witnesses.

CHARLES E. PAQUIN.
